DESIGN FOR A GLOVE

Sylvan M. Straus, Gloversville, N. Y.

Application October 11, 1938, Serial No. 80,368

Term of patent 3½ years

To all whom it may concern:

Be it known that I, Sylvan M. Straus, a citizen of the United States of America, residing in Gloversville, county of Fulton, and State of New York, have invented a new, original, and ornamental Design for a Glove, of which the following is a specification, reference being had to the accompanying drawing, forming part thereof, wherein,

Figure 1 is a rear view of a glove showing my new design.

Figure 2 is a front view of the glove shown in Figure 1.

The design is characterized by the arrangement of the large diamond perforated units with matching centers, forming the center panel on the back of the glove, flanked on each side by a series of small closely related perforated units as shown.

I claim:

The ornamental design for a glove, substantially as shown and described.

SYLVAN M. STRAUS.
